UNITED STATES PATENT OFFICE.

JULIUS C. HINTZ, OF DAYTON, OHIO.

WASHING-MACHINE.

1,239,600.

Specification of Letters Patent. Patented Sept. 11, 1917.

Application filed February 24, 1915. Serial No. 10,333.

To all whom it may concern:

Be it known that I, JULIUS C. HINTZ, a citizen of the United States, and a resident of the city of Dayton, in the county of Montgomery and State of Ohio, have invented certain new and useful Improvements in Washing-Machines, of which the following is a full, clear, and exact description, reference being had to the accompanying drawings, forming part of this specification.

My invention relates to washing machines of a new centrifugal type in which the clothes are placed in a perforated receptacle, water fed to the receptacle and the same then revolved rapidly so as to force the water through the clothes.

It has as its object the construction of a machine adapted to use this centrifugal principle, and in which there is provided a circulation system for the washing or rinsing water so that a continuous feed of water is not necessary.

I accomplish these objects as stated, and obtain various other advantages as will be detailed, by that certain construction and arrangement of parts to be hereinafter more specifically pointed out and claimed.

In the drawings,

Figure 1 is a central longitudinal section of the device complete.

Fig. 2 is a central cross section of the revolving clothes receptacle.

Fig. 3 is a side elevation of one of the water scoops.

The machine has an outer frame 1, of any desired kind, at the upper end of which is the journal 2 for the shaft 3 of the power pulley 4. The shaft 3 fits into a hollow shaft 5, which extends clear to the base of the machine.

Inside of the outer frame piece is a cylindrical shell 6, having an offset formed in it by an annular angle bar 7, which finds a seat on a cylindrical drum secured at the base of the machine. Set inside this latter shell in the base of the machine is a round trough pan, with flaring sides 8 extending up under the offset 7, so that all water running down inside the shell 6 from above will fall into the trough. The trough 9 is circular in shape, and its inner wall 10 extends inwardly and upwardly in a cone shape around the axis of the hollow shaft 5 already mentioned.

As shown in Fig. 2, the portion of the

shell 6 above the offset at 7 may be formed of two parts 6^a and 6^b, hinged together at 6^c. The other end of the two halves are bolted together at 6^d. This shell can be swung open to give access to the clothes receptacle to be hereinafter described, the flanges at 7 swinging away from the lower portions 7^a.

The hollow shaft 5 at its lower end has the V-shaped branches 11, 11, which extend down into the trough 9, and are provided at their extremities with the scoop mouths 12, 12, so that when the shaft rotates rapidly, the mouths will scoop up water which will be forced upwardly through the branches 7^a into the shaft, and up the shaft to the washer as will be described.

The shaft is supported on a post 13, having a cone-shaped end 14, which has a bearing in the roller bearing socket 15 in the base of the machine. The shaft has also a funnel shaped guard 16, that is secured to it above the branches 11 to prevent splashing of water. If any water should rise up or splash up over the inner wall 10 of the trough 9, the small chamber between these walls and the post 13 will become filled with water without doing any damage. Some outlet pipe 17 is provided for draining out the trough.

The receptacle for clothes is securely bolted onto the hollow shaft 5, and comprises a circular imperforate bottom plate 18 and a cylindrical side wall 19, which is provided with many apertures 20 for the escape of water driven centrifugally through the clothes.

The shaft has bolted onto it at 21 a number of vertical radial vanes or beaters 22. These beaters are all of the same width and a cylindrical screen 23 is secured around their outer edges to prevent the clothes from getting between the vanes. The vanes are also bolted at 24 to the bottom plate 18 of the receptacle.

As a top for the receptacle, a circular plate 25 is provided, domed at the center, and having an annular channel bar 26 around its periphery to seat over the edge of the cylindrical portion 19 of the receptacle. Hooks 27 on this top engage a cord 28 that is passed up over sheaves 29, 29, on the frame, and provided with weights 30, 30. Similar hooks 31 are mounted on the side pieces of the frame 1, to hold the ends of

the cords when the top is closed down over the receptacle.

The top when lowered into closed position is locked onto the shaft 5 by means of a tapered screwthreaded sleeve 32, which is split (not shown) so as to be contractible. A screw sleeve 33, tapered inversely, serves to compress the sleeve so as to frictionally lock it against the shaft.

10 A plug 34 closes up the shaft 5 near the top of the receptacle, and the shaft has apertures 35, 35, located below the plug to feed water from the shaft to the vanes. These need not be the only openings into the receptacle from the shaft, but care must be taken that plenty of water reaches the top of the receptacle.

The operation of the device is as follows: The cover or lid 25 is raised and clothing packed into the chamber between the screen 23 and the sides 19. Hot and soapy water is poured in the space inside the screen 23 and into the round trough pan 9, and the shaft 5 rotated. This rotation should be fourteen hundred revolutions to the minute, or more, and will result in a raising of water through the shaft, a forcing of it through the clothing, and a falling back into the trough, thereby setting up a circulation. Soap may be placed within the screen 23 if desired.

When washing is completed, the water is let out at 17, and rinse water inserted to rinse the clothes, and the clothes may be dried, ready for ironing, by revolving the machine without any water in it.

It is obvious that the mechanical expedients employed in the designing of this washer may be considerably modified by the use of equivalent structures.

40 The clothes should be soaked before being packed in as uniformly as possible so that they do not become unequally washed.

Having thus described my invention, what I claim as new and desire to secure by Letters Patent, is:—

1. In a washing machine, a central hollow shaft, a clothes receptacle on said shaft, a main receptacle around said clothes receptacle, means for rotating said shaft to cause said clothes receptacle to rotate, and scoops on the end of the shaft to raise water therein from the base of the main receptacle, said shaft having an aperture above the clothes receptacle to permit the water to fall into the clothes receptacle, and water dispersing means within the clothes receptacle, for the purpose described.

2. In a washing machine, a central hollow shaft, a clothes receptacle on said shaft, a main receptacle around said clothes receptacle, means for rotating said shaft to cause said clothes receptacle to rotate, and scoops on the end of the shaft to raise water therein from the base of the main receptacle, said main receptacle having a circular trough at the base to receive said scoops and said shaft having outlets to feed water to the clothes receptacle.

3. In a washing machine, a central hollow shaft, a clothes receptacle on said shaft, a water chamber at the center of said receptacle, said chamber having radial vanes, and said shaft having outlets into the water chamber, means for rotating the shaft, to rotate said clothes receptacle, a main receptacle around the clothes receptacle, and scoops on the end of the shaft to raise water therein from the base of the main receptacle.

JULIUS C. HINTZ.
